DESIGN FOR AN AUTOGRAPHIC REGISTER

Carl W. Sundberg, Birmingham, Mich., assignor
to The Standard Register Company, Dayton,
Ohio, a corporation of Ohio

Application March 5, 1941, Serial No. 99,366

Term of patent 14 years

To all whom it may concern:

Be it known that I, Carl W. Sundberg, a citizen
of the United States, residing at Birmingham,
Oakland County, Michigan, have invented a new,
original, and ornamental Design for an Auto-
graphic Register, of which the following is a
specification, reference being had to the accom-
panying drawings, forming a part thereof, in
which

Fig. 1 is a perspective view looking rearwardly
on the right side of an autographic register em-
bodying the new design.

Fig. 2 is a perspective view looking forwardly
on the left side.

Fig. 3 is an elevational view of the right side.
Fig. 4 is an elevational view of the left side, and
Fig. 5 is a front elevational view thereof.

I claim:

The ornamental design for an autographic
register, substantially as shown.

CARL W. SUNDBERG,
